Primary Examiner — Barbara Fox

Assistant Examiner — Kristin E Reed

(74) Attorney, Agent, or Firm — Brake Hughes
Bellermann LLP(57) **CLAIM**

What is claimed is an ornamental design for a media sharing device with graphical user interface, as shown and described herein.

DESCRIPTION

The FIGURE is a front view of a media sharing device with graphical user interface showing my new design.

The broken lines shown in the drawings depict portions of the media sharing device with graphical user interface that form no part of the claimed design.
